KEY-OPERATING ARRANGEMENT FOR SHORT-WAVE TUBE TRANSMITTERS

Application filed August 18, 1925, Serial No. 51,002, and in Germany September 4, 1924.

Our invention relates, broadly, to tube transmitters for transmitting communications by means of radio frequency electromagnetic waves, and, more particularly, to a keying arrangement especially adapted for use with very short wave lengths.

An object of the invention is to provide an arrangement of the above kind that will be simple in construction and operation, one which will permit the key to be placed at any desired distance from the transmitting tube and one which will not cause sparking at the key contacts.

Other objects will be apparent from the following description and claims when considered with the accompanying drawing, in which.

Fig. 1 represents a tube transmitter with one embodiment of our invention applied thereto, and

Fig. 2 represents a tube transmitter with another embodiment of our invention applied thereto.

An arrangement is known for detuning keying which comprises two different oscillation circuits coordinated to a generator tube, which are alternately rendered operative in performing the key work. This arrangement will always be used to advantage, if, in such detuning key-work, a considerable difference in wave length is to be obtained.

Now, when working with very short wave lengths, it has been found that successful telegraphic operation is feasible even at extremely small change in wave length. Indeed, a change of the fraction of 1:1000, is practicable for keying purposes. There are various means adapted to produce wave va-

riations of such small degree. For instance, the oscillation circuit of the transmitter tube can be detuned by varying either the self-inductance or the capacitance in the rhythm of the key signals. The changes in self-inductance, for instance, can be obtained by short-circuiting a turn or spiral of the coil, or a part thereof. By this arrangement, there must flow thru the key always a certain high frequency current which causes spark formation at the key contact. The same thing

happens if the capacity be changed, instead of the inductance.

Now, according to the present invention, an ohmic resistance is inserted in a direct current circuit of the transmitter tube, and the key in parallel to the same. The said ohmic resistance could be arranged, for example, in the direct current anode lead. The resistance being either short-circuited or left in circuit, the same becomes causative of a small variation of the anode direct current potential, and consequently of the generated wavelength. The advantage which this scheme offers over the detuning method of keying previously mentioned resides in that the key is inserted in a direct current lead, so that it can be arranged at any desired distance from the transmitter.

More appropriate than the arrangement of the resistance in the anode lead is the disposition of the same in the direct current grid lead, since the currents flowing therein are very small. This arrangement offers the advantage that the energies to be keyed become of very low value, with the consequence that sparking is wholly precluded.

Referring to Fig. 1 of the drawing, 1 denotes a usual type of three-element electron discharge tube comprising a heated filamentary cathode, a cold plate anode and a cold grid shaped control electrode, all sealed within an evacuated envelope. This tube has its circuits connected to generate sustained oscillations. In the particular embodiment shown, the oscillation circuit 2 comprising capacitance 10 and inductance 11 connected in parallel determine the generated wave length.

This circuit is connected to the anode of tube 1 thru a blocking condenser 12 and to the control electrode thru a grid condenser 3. The cathode of tube 1 is connected to an appropriate point on inductance 11 by the adjustable lead 13.

Across the grid condenser 3 is a grid leak 4 to determine the amount of negative potential which the grid shall accumulate during operation. Also connected across the grid condenser 3 is a key 5 connected thru two

choke coils 6 for keeping high frequency from the key 5.

Anode current is supplied by source 14 acting thru inductance coil 15.

5 It will be easily seen that, when key 5 is depressed, the grid leak 4 and grid condenser 3 will be short-circuited, permitting the bias on the grid to change, this causing the generated wave length to change.

10 In Fig. 2 the same reference characters refer to the same parts as in Fig. 1. The tube 1 is connected to generate sustained oscillations. However, in this case, instead of varying the direct current flowing from 15 the grid, the direct current flowing in the anode circuit is varied by keying. This will also cause the generated wave length to change, as pointed out above.

Having described our invention, we are 20 entitled to all modifications thereof as fall fairly within its spirit and scope as defined by the following claims:

1. In combination, a three-element electron discharge tube having a control electrode 25 condenser to enable the control electrode to accumulate a bias; a leak across said condenser; means comprising a tuned circuit connected to the anode and control electrode of the tube for causing said tube to produce 30 oscillations; and means for short-circuiting said leak consisting solely of a key and a pair of choke coils.

2. In combination, a three element electron discharge tube; means for causing said tube 35 to produce oscillations including a tuned circuit connected across the anode and the control electrode of said tube; said tuned circuit comprising an inductance and capacitance; a control electrode condenser interposed between said circuit and said control electrode; a leak across said condenser, means for short-circuiting said leak consisting solely of a key and a pair of choke coils, and a lead from the cathode of said tube to 40 a point on said inductance.
